No. 880,716.

PATENTED MAR. 3, 1908.

B. R. CHARLES.
ELECTROTHERMAL GARMENT.
APPLICATION FILED OCT. 16, 1907.

UNITED STATES PATENT OFFICE.

BURTON R. CHARLES, OF PORTLAND, OREGON.

ELECTROTHERMAL GARMENT.

No. 880,716.

Specification of Letters Patent.

Patented March 3, 1908.

Application filed October 15, 1907. Serial No. 397,582.

To all whom it may concern:

Be it known that I, BURTON R. CHARLES, of Portland, county of Multnomah, and State of Oregon, have invented a new and useful 5 Improvement in Electrothermal Garments, of which the following is a specification, reference being had to the accompanying drawing as constituting a part thereof.

This invention relates primarily to an 10 electrothermal garment, to be worn on the body, and consists in arranging a series of insulated wires in the garment material, for treatment of diseases. Garments of this 15 general type are known to be old in the art, but with such, they are designed to be used for medicinal purposes only. In other words, the wire terminal connections, have been arranged in such manner as to preclude the 20 wearing of the garment for ordinary house robe purposes.

According to my present invention I employ the usual wiring in the fabric, and have the terminals with the plug and controlling switch in the pockets, thereby concealing 25 them when the garment is used as a robe. The plug and switch are connected to a sufficient length of wire to enable them to be easily and conveniently handled when it is desired to supply current for treatment.

30 The invention also comprehends improvements in the specific details of construction, which will be hereinafter referred to and particularly pointed out in the claims.

In the drawings—Figure 1 is a front view 35 of a thermal garment with my improvement applied. Fig. 2 is a rear view of the same, the pockets being broken away to show the plug and switch. Fig. 3 is an enlarged view 40 of the wire and plug, and one of the pockets, the plug being shown in dotted lines in the pocket. Fig. 4 is a similar view showing the switch.

The numeral 1, indicates a garment, such as employed to substantially envelop the 45 body of a wearer. The garment is provided with pockets 2, and 2^a, and the usual drawing string 4.

Interwoven or otherwise placed in the 50 garment are insulated wires 5, the terminals 5^a, 5^a, and 5^b, 5^b, of which pass through the outer layer of the body of the garment inside the pockets 2, and 2^a. The wires are coiled on the body of the garment as indicated at 1^b, and then stitched to hold said 55 coiled portions in position and to prevent the coils in the fabric being pulled out. To

the terminals 5^a, 5^a, is secured a plug 8, adapted to be connected to a socket 9, of an ordinary incandescent electric lamp. The length of the wires outside the body of the 60 garment is quite sufficient to permit of the plug being withdrawn from the pocket for convenient handling when using the improvement for treatment.

The terminals 5^b, 5^b, extend through the 65 garment at a point inside the pocket 2^a, and extends outwardly therefrom a short distance. To the ends of these terminals 5^b, 5^b, is a switch 12, to enable a wearer of the garment to turn the current on or off at will. 70

In use, the garment is placed on the body of the wearer, and the plug 8, is connected with a service current, then the switch is turned on to admit the current to the wires in the garment. After the patient has been 75 treated sufficiently, the plug is disconnected and is stored in the pocket 2, and the switch is likewise stored in the companion pocket 2^a. Inasmuch as the plug and the switch can be so conveniently stored, and concealed, obviously the robe can now be used for ordinary 80 house purposes, without letting it be known it is a thermal garment, or having the connections loosely hanging to be in the way.

I am aware it is old to provide a thermal 85 garment with contacts whereby electric current is passed through the wires, but I do not claim broadly such a construction. My purpose being solely to conceal the switch and plug, and have them out of the way that the 90 garment may be used for ordinary purposes.

What I claim is:

1. A thermal garment provided with a pocket, wires in the garment, the wires passing through the garment into the pocket, a 95 plug on the terminals of the wires to form electric connection, said plug and the wires connecting the same with the garment adapted to be carried in the pocket and concealed.

2. A thermal garment comprising a body 100 portion having a pocket, wires in the body portion, said wires extending outside the body and fastened thereto inside the pocket, a contact plug on the terminals of the wires, said plug and the wires connecting the same 105 with the garment adapted to be concealed in the pocket when the garment is used as an ordinary robe.

3. A thermal garment comprising a body portion having pockets, wires in the body 110 portion, said wires extending outside the body and fastened thereto inside the pockets,

a contact plug on the terminals of the wires in one pocket, and a switch on the terminals of the wires in the other pocket, the plug and switch and the wires connecting the same with the garment adapted to be concealed in the pockets when the garment is used for an ordinary house robe.

4. A thermal garment consisting of a body portion having pockets, wires in the garment, the terminals of the wires extending through the body of the garment at a point inside the

15 pocket, said wires being coiled on and secured to the garment at a point where the wires pass from said garment, and a plug on the ends of the terminals, said plug adapted to be concealed in the pocket.

In testimony whereof I affix my signature in presence of two witnesses.

BURTON R. CHARLES.

Witnesses:

CECIL LONG,
S. M. PHILBRICK.
